COMBINED STRETCHING AND STAPLING DEVICE

William Spiegel and Jacob Spiegel,
Philadelphia, Pa.

Application November 2, 1950, Serial No. 193,552

1. Claim. (Cl. 1—45.6)

1

This invention relates to a combined stretching and stapling device of the general type disclosed in McClure Patent 2,009,116 and Friedman Patent 1,798,664.

One object of the invention is to produce an improved device of the type set forth.

In the fur trade it is necessary to stretch the hide and simultaneously to tack it to a board or work table and, as far as is known, all prior art devices of this type were so constructed that the staple was driven all the way in. In other words, the horizontal or bight portion of a standard, U-shaped staple was driven into tight abutment with, or perhaps slightly into the surface of the hide. This makes it difficult to remove the staples without damaging the hide.

It is therefore a further object of the invention to produce a hide stretching and stapling device whereby the staples are only partly driven through the hide so that the staples can be grasped by their upper, exposed, portions and pulled out without damaging the hide.

If a staple is driven only part way into the hide, a conventional stapler can only be moved away from the partly driven staple by raising the stapler high enough to clear the upper portion of the staple which projects above the hide. This is so cumbersome and time consuming as to render the device impractical.

It is therefore a further object of the invention to produce an improved stapler which can be moved away from a partly driven staple without having to raise the stapler above the upper projecting portion of the stapler.

A hide may be stretched by exerting a pulling action on one edge thereof or it may, where space is limited, have to be stretched by exerting a pushing action on one edge thereof. Also, when the hide is stretched, by a pushing, instead of by a pulling, action, it is desirable to provide a fixed barrier or straight edge against, or toward which, the edge of the hide is to be pushed.

It is therefore a still further object to produce an improved device of the type set forth which is adapted for stretching a hide by pushing as well as by a pulling action.

After the edges have been tacked in stretched condition, it is frequently necessary to tack intermediate portions of the hide without any simultaneous stretching.

It is therefore a still further object of the invention to produce an improved device of the type set forth which is adapted for use as a stapler only or as a combined stapling and stretching device, without materially altering the structure of the device itself.

2

These and other objects are attained by this invention as set forth in the following specification and as shown in the accompanying drawings in which:

Fig. 1 is side elevational view of combined stretching and stapling device embodying the invention, the same being shown when not in use.

Fig. 2 is a view, partly in section and partly in elevation, of the device shown in Fig. 1, the same being shown when used for pulling and stapling a hide to a work table.

Fig. 3 is an enlarged view of the portion of Fig. 2 which is bracketed with broken lines.

Fig. 4 is an enlarged, fragmentary, horizontal sectional view illustrating the use of the device for pushing the edge of the hide toward a straight edge.

Fig. 5 is a fragmentary view showing how the lower jaw may be locked in closed position when the device is to be used for stapling only.

The stapling device shown may, except as pointed out below, be conventional and, as such, it includes the usual magazine 10 for storing a quantity of staples, a spring loaded pusher 12 for pushing the staples 14 to a position to be struck by hammer 16 which is operated by impact applied to knob or head 18. The operation of the stapler thus far described, that is the driving, successively, of individual staples is conventional and is therefore not shown nor described in detail.

In order to adapt the stapling device to grasping and pulling the edge of a hide, or the like, it is provided with an upper, fixed serrated jaw 20 formed on, or suitably secured to the underside

35 of the stapler body, and a lower movable serrated jaw 22 which is pivoted at 24 to the body of the stapling device and which is actuated by means of handle or lever 26. The handle 26 is normally biased, by a spring 28, to the upper position of

40 Fig. 1 in which the movable jaw 22 moves away from fixed jaw 20, it being understood that, when the handle is moved, against the action of spring 28, to the lower position of Fig. 2, the lower jaw 22 moves into abutment with upper jaw 20 so as firmly to clamp the edge of a hide or other sheet

45 material 30 to be stretched and tacked to a board or a work table 32 detachably mounted on a support 34. By the construction thus far described, the edge of a hide can be grasped and the hide stretched to the desired extent and in the desired direction over work table 32 and, by means of a blow applied to knob 18, a staple 14 will be driven through the hide and into the work board.

50 55 If the bottom edge 36 of the stapler were to come into contact with the hide, as it would in

conventional staplers, the staple will be driven all the way in. But, by the interposition of the jaws 20 and 22 between the bottom edge 36 of the stapler and the support 32, the staple can be driven in only part way. In other words, when the hammer 16 reaches its lowermost position, it will be flush with the bottom edge 36 of the stapler and the staple will only be driven to the extent shown in Fig. 3. It is true that the extent to which a staple is driven can be controlled by shortening the stroke of the hammer 16 but that involves making changes in the structure of the stapler itself. This would not be desirable because of the re-tooling costs and because shortening the stroke of hammer 16 will make the stapler useless for ordinary use. By this invention, the stapler construction is undisturbed so that if the jaws are dispensed with a completely operative conventional stapler will remain.

When it is desired to remove the staple, it can be grasped by its upper, exposed portion and pulled out without the necessity of "digging" it out of the hide which would be necessary if the staple were driven in until the cross piece or bight portion 38 thereof abuts tightly against, or is somewhat embedded in, the surface of the hide or other material. It will be understood that the thickness of the jaws 20 and 22 should be such as to accomplish this purpose but that it is not otherwise critical.

The device is further provided with a rigid bar 44 which serves as a handle for carrying the stapler and for providing a fixed surface towards which the lever 26 is moved to actuate the lower jaw 22 to the clamping position of Fig. 2. A finger rest 46 is preferably provided at the free end of the handle 44 to prevent the device from slipping out of the hand of the user. When the stapler is not being used to stretch the hide but merely for fastening it to the board 32, the jaws 20 and 22 are locked in closed position.

In order to clamp the lower jaw 22 in its closed position when the device is to be used for stapling only, a U-shaped latch 48 is pivoted to the end of the handle 44 and is adapted to engage the adjacent end of lever 26 in the manner shown in Fig. 5. The bight portion of the latch 48 is preferably of wedge or cam shape, as shown at 50 in Fig. 5, firmly to hold the lower jaw in closed position regardless of inaccurate manufacture or of reasonable yielding of lever 26 or handle 44.

When the stapler is to be used for stretching the hide by exerting a pushing action on the hide, instead of by pulling it, the jaws 20 and 22 are locked in closed position and the bottom serrated surface 42 of the lower jaw is brought into engagement with the hide. Then, by pushing downwardly and forwardly, the hide is stretched in that direction.

It is sometimes necessary, in stretching the hide by a pushing action, to bring the edge of the hide close up to or against a fixed barrier or straight edge 52. But, with the lower portion of the front wall 53 removed, the staple is exposed and abutting the nose of the stapler against straight-edge 52 will wedge the staple against the straight edge and will interfere with the movement of the staple. To guard against this, the upper jaw 20

is provided with forwardly projecting bumpers 54 which are disposed on either side of the staple and which, as shown in Fig. 4, abut the straight edge while the staple itself remains spaced from the straight edge. By this arrangement, the edge of the hide can be pushed up against the straight edge and the staple remains free to move.

From the foregoing it will be seen (1) that the jaws 20 and 22 can be used to grasp and pull the hide, (2) that they can be locked in closed position and used to push the hide, (3) that they act as a spacer to limit the extent to which the staple is driven without the necessity of making any change in the hammer actuating mechanism, (4) that by cutting away the lower portion of the front wall 53 of the stapler, the stapler can be backed off from a partly driven staple instead of having to be raised above the staple which, unless done with extreme care may bend or wholly dislodge the partly driven stapler, (5) that the bumpers 54 permit the edge of the hide to be pushed up against the straight edge while preventing the exposed side of the staple from contacting the straight edge.

While the device has been shown as adapted for driving staples, it is to be understood that the various improvements above disclosed can be readily applied to a device of the type which drives nails such as that disclosed in the Friedman patent above mentioned. Therefore, in the appended claim, the word "staple" is to be understood as including nails or the like.

What we claim is:

A combined stapling and stretching device including a magazine adapted to contain staples, a driving hammer, means for moving said staples to a position in which they can be struck by said hammer, a fixed jaw carried by, and projecting below, the face of the device which faces the material into which the staples are to be driven, a movable jaw pivoted below said fixed jaw, and a lever for moving said movable jaw to a first position in which it abuts said fixed jaw, and to a second position in which it is spaced from said fixed jaw, the abutting surfaces of said jaws being roughened for frictional engagement with said material.
